UNITED STATES PATENT OFFICE

FRANCIS J. O'DONNELL, OF MEDWAY, MASSACHUSETTS, ASSIGNOR TO JOSEPH M. HERMAN SHOE COMPANY, OF BOSTON, MASSACHUSETTS, A CORPORATION OF MASSACHUSETTS

SHOE

Application filed June 29, 1928. Serial No. 289,095.

The present invention relates to an improvement in shoes.

Persons engaged in handling heavy things such as pig iron, structural steel, stock and other things are sometimes injured by the falling of things upon their toes. The use of steel or metal caps for such shoes is objectionable because, if crushed by a falling object, the foot is with difficulty withdrawn from the crushed toe of the shoe. It is a requisite, therefore, of shoes for use by such persons that the toe be strong and stiff and still capable of being cut with a knife to be removed from an injured foot. In many cases the shoes are exposed to oil, and sometimes the box toe stiffeners, such as those made of leather, are so softened and rendered pliable and sleazy by the oil, that they give no stiff protection to the foot after having become saturated with oil. Box toe stiffeners made of asphalt-treated felt, when exposed to oil, become soft and pliable and require to be protected from the access of oil in order to preserve their stiffness and strength.

The object of the present invention is to produce a shoe having a strong, stiff toe which will protect the foot against injury by the dropping of things on it, and which at the same time will retain its stiffness and strength by preventing the access of oil to the stiffener or stiffening material employed.

According to the present invention the shoe is constructed with an oil tight pocket within which the stiffener is encased to prevent the softening effect of the access of oil to the stiffener. The invention further consists in details of construction hereinafter described and particularly defined in the claims.

In the accompanying drawings illustrating the preferred form of the invention, Fig. 1 is an elevation of a shoe showing the shoe cap, and Fig. 2 is an enlarged detail drawing of a portion of the cap and vamp of the shoe at the joint.

The illustrated embodiment of the invention is described as follows: The shoe comprises a vamp 10, a sole 11 and a toe portion indicated in a general way by the reference character 12. The shoe is of the Good-

year welt type provided with an insole 13 and welt 14, and between the insole and the sole is a layer of hard fibre 15 for the purpose of stiffening and strengthening the sole and contributing to the wear of the sole and prevention of access of oil to the toe portion. The toe cap 16 is of the usual form and laps over the forward edge of the vamp 10, as shown in Fig. 2. Underneath the rear edge of the toe cap is provided a strip of stay-tape 17, which is used to prevent any extrusion of glue through the perforations with which the rear edge of the cap is usually provided.

The box toe stiffener comprises two pieces 18 and 19 of asphalt-impregnated felt. This stiffener is, therefore, a double thickness stiffener, and taken together they form a strong, stiff support for the toe portion, and an excellent protection to the foot of the wearer. This box toe stiffener is encased or pocketed between two layers of oil-impervious cloth 20 and 21. These stiffener covers 20 and 21 are made of enamel cloth to render them oil-impervious. Inside of the shoe is the usual lining 22.

The upper is assembled as follows:—The toe cap, stay-tape and the outer stiffener cover 20 are sewed together by a dry-thread seam 23, which unites the rear edge of the toe cap, stay-tape and outside box toe stiffener cover together at the seam. The two pieces of the box toe stiffener (which for convenience in handling are tacked together by sheet metal fasteners) and the inside stiffener cover are then applied in the position shown in Fig. 2, and then a second wax-thread seam 24 of stitches is sewed through the toe cap, stay-tape, the outer cover, the vamp, both layers of the stiffener and the inside stiffener cover. This seam is a wax-thread seam, as stated, in order to secure a tight oil-resisting seam to prevent entrance of oil to the box toe stiffener from above. Either before or after the assembly of the parts of the box toe, as described, the other portions of the upper are united by the usual seams.

The shoe is then ready for the making. Preliminary to the insertion of the last and the pulling over operation, the stiffener is heated in the usual way on a steam table, and

then glue is applied to the surface between the cap and the outer stiffener cover, between the outer stiffener cover and the stiffener, and between the stiffener and the inner stiffener cover, and paste between the inner cover and the lining. The last is inserted in the shoe, the insole is applied and the pulling over operation is performed. Next the shoe is lasted, and the inseam is sewed. The heating of the stiffener of the type referred to renders it pliable and easily bent and formed to the contour of the last. In some stiffeners the softening would be accomplished by treating with a vapor or liquid adapted to soften the stiffener.

The shoe is provided with an oil-protecting cover or pocket, which is closed at the upper edge of the cap by the wax-thread seam and at the outer edge of the cap by the inseam, thus preventing the ingress of oil or water or perspiration to the stiffener, and preserving it in its strong, stiff condition.

A shoe toe made according to this invention was cut off of a shoe, immersed for two weeks in a body of oil, removed and then subjected to vertical pressure and found to be able to support, without intolerable distortion, a weight of approximately 300 lbs.

The glue by which the several parts are united contributes to the stiffness, strength and oil-resisting quality of the shoe toe. The outer stiffener cover and cap on the outside, and the inner stiffener cover and shoe lining on the inside, form not only a resistance to the ingress of oil, but also form heat insulating layers which prevent the heat from striking through to the stiffener, and thereby softening it.

Having thus described the invention, what is claimed is:

1. A shoe having its toe portion provided with a box toe stiffener of normally strong, stiff material, a stiffener pocket or enclosure of two pieces of enamel cloth, one on each side of the stiffener, the edges of the enamel cloth being sewed together to close the pocket and to protect the stiffener from access of oil.

2. A shoe as defined in claim 1 in which the pocket or enclosure material is glued to the stiffener.

3. A shoe having a toe cap, a vamp extending to and lapping under the rear edge of the toe cap, being united thereto by a dry-thread seam of stitches, two oil-proof box toe stiffener covers, and a stiffener between them, the covers, stiffener and toe cap being united by a wax-thread seam at their rear edges, and by the inseam at their outer edges, to seal the stiffener from the access of oil thereto.

4. A shoe as defined in claim 3 in which the stiffener covers are glued to the stiffener.

5. A shoe having its toe portion provided with a box toe stiffener and an enclosing

70 pocket or enclosure therefor formed of oil-resisting materials, the edges of the pocket being united by a seam of stitches across the top of the toe and by the inseam around the edge.

In testimony whereof I have signed my name to this specification.

FRANCIS J. O'DONNELL.
